EARTH BORING AND CONDUIT LAYING
MACHINE

Steven L. Rose, Arcadia, Calif., assignor to Calweld
Inc., Los Angeles, Calif., a corporation of California
Filed Nov. 24, 1961, Ser. No. 154,522
5 Claims. (Cl. 173—148)

This invention relates to an earth boring and conduit laying machine and more particularly to a machine for boring relatively large diameter holes on a substantially horizontal plane or on a slightly inclined plane and simultaneously positioning conduit in the bore.

Heretofore, when laying pipe, culverts, oil lines, or other conduits when "surface ditching" is used, it is necessary that surface ditches be dug, the pipe laid in the ditches and then the ditch back-filled with earth to cover the pipe up once it has been laid. When surface ditching has been used under roadways, etc., it has been necessary not only to backfill, but to resurface the road once the pipe, culvert or lines have been put in position. This method has produced traffic congestion, inconvenience and created an unsightly area. In some cases dangerous conditions have resulted when deep open ditches and trenches have been left unattended.

An object of the invention is to provide a boring machine which drills under streets, highways, railroad tracks, airport runways, parking lots, etc., without disturbing the surface or requiring the diversion of traffic while the street or area is disrupted with surface ditches.

Another object of this invention is to provide a boring machine which may be used in an open pit prepared for the machine adjacent the area to be drilled or bored.

Another object of this invention is to provide a base having hydraulically-operated rams mounted therein, a slideable rotatable kelly mounted on said base and a means for rotating said kelly and activating the rams.

A further object of this invention is to provide a key coupling for an auger flight or section and the kelly whereby the auger may be rotated boring through the earth or for the joining of two auger flights.

Another object of this invention is to provide a push yoke means activated by the rams to urge the auger flight and pipe casing into the earth.

A further object of this invention is to provide a kelly keeper to lock the push yoke means to the kelly without impairing the torque capacity of the kelly during the drilling operation.

A more specific object of this invention is to provide a telescoping hydraulically actuated ram means whose length of forward thrust may be controlled and which will eliminate the need for various lengths of push rods for forcing the auger flight and pipe casing into the bore.

A further object of this invention is to provide a motor mounted on a base with the drive shaft and transmission to the rear of said base and the radiator to the front of said base whereby the transmission and shaft will be in close proximity to a reduction gearing means between the shaft and the kelly means, and also so that more air may be circulated to the radiator for cooling the engine.

Further objects and advantages of this invention will appear during the course of the following part of this specification, wherein the details of construction of one embodiment thereof are described with reference to the accompanying drawings, in which:

FIGURE 1 is a side elevational view of the boring machine, auger flight and casing in a pit ready for use;

FIGURE 2 is a top-plan view of the device illustrated in FIGURE 1;

FIGURE 3 is a side elevational view of the boring machine where the hydraulic rams have completed one

2

forward push and a part of an auger flight and casing have been forced into the earth;

FIGURE 4 is a view similar to FIGURE 3, but where the hydraulic ram has completed its second forward thrust; 5 forcing the auger flight and casing further into the earth;

FIGURE 19 is an exploded detail view of the pin and locking mechanism for the kelly means and auger flight;

FIGURE 20 is a view similar to FIGURE 12, showing the guide arms as used for pipe or casing of a larger diameter than that which is illustrated in FIGURE 12;

FIGURE 21 is a sectional view taken on line 21—21 of FIGURE 7; and

FIGURE 22 is a schematic view of the hydraulic system to actuate the hydraulic ram assemblies.

The boring machine generally designated 30 includes a generally-rectangular shaped base or platform 32 having a front wall 34 and rear wall 33. Mounted on the base 32 is a motor 36, fuel supply tank 38 for the motor, and motor transmission 40. Also mounted between the upper surface 37 and lower surface 39 of the base 32 is a kelly bar 42 which is extendable through the front and rear walls 34 and 33 of the base 32 and extends through a push yoke generally designated 44. Also mounted within the base 32 are a pair of telescoping hydraulic rams generally designated 46 which extend through the front wall 34 and are secured to the push yoke 44.

For drilling or boring under the surface of the earth, an open pit 48 is dug adjacent the area 50 to be drilled. The pit has a generally horizontal floor 52 for horizontal drilling or an inclined floor from the horizontal, if it is desired that the bore be slightly inclined from the horizontal. Further, at the rear end wall 49 of the open pit 48 a small bore 53 is drilled to accommodate the kelly bar 42 for reasons to be explained. The base 32 has four screw jacks 54 which may be extended outwardly from the base and engage the side walls 55 and 57 of the open pit 48 to stabilize the machine and to aid in main-

65

60

65

taining it in a stationary position throughout the drilling operation.

To bore the hole, when it is desirable to include a casting within the bore, an auger flight or section generally designated 56 is secured to the kelly bar 42. The auger flight includes a shaft 58 carrying a conventional spiral auger 60 at the end of which is a conventional drilling bit assembly 62. The auger is surrounded by a casing or conduit 64 which is normally generally the length of the shaft 58 with the drilling bit assembly 62 attached thereto. This conduit 64 is slightly larger in diameter than the diameter of the auger 60.

The motor 36 is mounted on the upper surface 37 of the base 32 with the radiator 35 facing into the open pit 48 toward the area where the drilling is done. In this way effective cooling of the engine is possible. Also this placement will put the transmission 40 at the rear of base 32 over the area housing the reduction gearing assembly to drive the kelly 42. The motor transmission 40 is connected to a clutch 66 and is of the type well known in the art having several forward speeds, and a reverse speed.

The reduction gear assembly generally designated 67 may be sealed within the base 32 in a housing including forward and rearward support bulkheads 84 and 85 which extend vertically from the lower surface 39 and are secured thereto, cap plate 87, a short support bulkhead 89 and a second cap plate 91. This housing extends between the respective side walls of the base 32 and will keep the assembly 67 dirt free. The cap plate 87 may be secured to bulkheads 85 and 89 by means of cap screws 87a. Also the gear assembly 67 may be lubricated from an oil reservoir 95 at the bottom of the housing which covers a portion of gear 90. The lubrication is accomplished by the gear 90 throwing oil upward as it rotates.

A drive shaft 68 extends from the clutch 66 through bearings 70 and 72 which are mounted in bulkheads 89 and 85 respectively. Mounted on the shaft between the respective bearings 70 and 72 is a triple sprocket gear 74. Mounted below the drive sprocket gear 74 and in alignment therewith is a larger triple sprocket gear 76 journaled on a shaft 78 which is mounted between two bearings 80 and 82 which are in turn mounted in the bulkheads 84 and 85 respectively; also journaled on the shaft 78 is a spur gear 86. Three sprocket chains 88 connect the two sprocket gears 74 and 76. The spur gear 86 engages a relatively large spur gear 90 which is journaled on an enlarged end section 96 of a kelly drive tube 92. It should be noted that the kelly drive tube 92 and extension 96 have longitudinal passages which are square in cross section and accommodate the kelly bar 42 which is also square in cross section. The end extension 96 is mounted within a pair of bushings 94 mounted in the respective bulkheads 84 and 85 on either side of the spur gear 90. In operation, when the motor 36 is running the variable speed transmission 40 is engaged, thereby rotating the drive shaft 68 which in turn will rotate the sprocket gear 74 and sprocket gear 78 through sprocket chains 88, turning spur gears 86 and 90. As the spur gear 90 is turned, the kelly drive tube 92 and extension 96 will revolve. By the above described gearing arrangement a reduction may be effected to enable the kelly bar 42 to develop the required torque needed for drilling, depending upon the substance to be drilled.

Adjacent the front wall 34 of the base 32 and supported on the surface 39 there is provided a split bearing housing 98 mounting a split bearing 100 through which the kelly drive tube 92 passes. The drive tube 92 is formed with an annular bearing flange 102 which rotates in the bushing 100.

The drive tube 92 at its end 104 adjacent the wall 34 is formed into a collar extension 105 generally square in cross section through which the kelly bar 42 will pass.

Mounted on the collar extension 105 is a plunger lock assembly 106 having a housing 105a with a plunger 108 having a rounded end extending through the housing. A compression spring 110 is provided around the plunger 108 and secured thereto within the housing 105a urging the plunger away from the collar extension 105. A dimple 112 is formed in the top surface of the kelly bar 42 which may be engaged by the plunger 108 when aligned with an aperture 109 in the collar extension 105. The spring 110 being of the compression type may be overcome with downward pressure on the plunger 108 to engage the kelly bar 42 and restrain the kelly bar against horizontal shifting within the drive tube 92.

The telescoping ram assemblies 46 are each mounted within the base 32 between upper and lower surfaces 37 and 39 on each side of the kelly bar 42 and on parallel axes therewith. The assemblies extend between the bulkhead 84 and the front wall 34. Each assembly 46 comprises an outer cylinder 116 capped by a rear plate 118 having a mounting stud 120 extending rearwardly from the plate 118 through the bulkhead 84 and held thereto by means of nut 122. The cylinder at its forward end is capped by a cylinder head 124 generally T shaped in external appearance and having a cylindrical portion fitted within the cylinder 116, and a flanged portion 124a of the head 124 is secured to an annular flange 126 on cylinder 116 and the front wall 34 of the base 32 by means of a plurality of cap screws 128.

A piston 130 slidably mounted within the cylinder 116 is secured to a hollow, circular push rod 132 by means of a plurality of screws 134. A stop sleeve 136 mounted on the hollow push rod 132 forward of the piston 130 will act to stop the forward movement of the piston 130 when it engages a rear face 138 of the cylinder head 124. The cylinder head 124 is provided with a brass or other metallic bushing 140 through which the hollow push rod 132 is slidably mounted, and a retaining cap 142 is secured to the cylinder head 124 by means of cap screws 144 exteriorly of wall 34. There is also provided an annular dirt seal 146 in the forward face of the retaining cap 142 engaging the rod 132. Within the hollow circular pushrod 132 is slidably mounted a circular push rod bar 148. Adjacent the forward portion of the push rod assembly 46, the push rod 132 and the push rod bar 148 are formed with alignable openings 150 to receive a locking pin 152 to releasably interlock the push rod bar in the push rod and cause simultaneous movement of the two parts. Also there is an opening 153 at the rear end of the bar 148 which when aligned with opening 150 can receive pin 152 to maintain the push rod bar in an extended position relative to the push rod.

The ram assemblies are each provided with hydraulic couplings 154 and 156. The coupling 154 provides fluid communication through bulkhead 84 and rear plate 118 for hydraulic fluid from line 158 to force the piston, push rod 132 and push rod bar 148 forward toward the cylinder head 124. When it is desired to retract the extended push rod and push rod bar, hydraulic fluid will be forced through a hydraulic fuel line 160 through coupling 156 and into the cylinder 116. As the fluid thus flows into the cylinder it will urge the piston 130 rearwardly, and at the same time the fluid which has been forced in through coupling 154 is expelled in a conventional manner.

The hydraulic system diagrammatically illustrated in FIGURE 22, for actuating the ram assemblies 46 preferably includes a fluid reservoir 260 having a main fluid line 262 leading to a hydraulic pump 264. There is shown in phantom lines a drive connection between the pump 264 and motor 36 to impart rotary motion to the pump 264. The main fluid line 262 continues from the pump 264 to a four way, two position flow control valve 266. There is also included a bypass line 268, a pressure regulator valve 269, and a return line 268a. The valves 266 and 269 normally are within a single housing and may be of the commercially obtainable type such as a "Zeno 94D." The fluid

line 158, previously identified, extends from the valve 266 to the respective hydraulic ram assemblies.

The fluid lines 160, previously identified, extend from the opposite ends of the respective hydraulic ram assemblies 46 to the valve 266. A fluid return line 270 extends from the valve 266 to the reservoir 260 and includes a filter 272 positioned in the line 270.

In operation when it is desired to force the pistons 130 outward the valve 266 is set so that fluid will pass from line 262 through line 158, and at the same time allow fluid to be bled off through line 160 and 270, through filter 272 to the reservoir 260. When it is desired to force the pistons 130 inward the valve 266 may be set to allow fluid from line 262 to pass into line 160, and at the same time allow fluid to be bled off from line 158 into line 270 through filter 272 to the reservoir.

The pressure regulator valve 269 may be set for any desired pressure so that should the system build up pressure above the pressure setting the fluid will be bypassed through line 268, valve 269 and line 268a back to the reservoir 260.

The valve 266 may be of a manually operable type or automatically controlled, in accordance with selected conventional practice.

The push yoke assembly 44 includes an elongated generally hollow housing 44a having a front plate 163 and a rear plate 166 both of the same general exterior configuration, being narrow at the ends thereof and flared to a width in the middle to accommodate a kelly thrust sleeve or tube 168 which extends through the respective plates 163 and 166. A flat sleeve cap 164 is fitted around the sleeve 168 and a flange 174 extends through the plate 163 into the hollow interior of the housing. The cap 164 is secured to the plate 163 by means of cap screws 165.

Fitted within annular flange 174 of cap 164 is a thrust sleeve bearing 176. The kelly thrust sleeve 168 is formed with an annular stepped flange 178 intermediate its ends. An additional thrust bearing 180 is fitted within the housing rearwardly of the flange 178 which engages the first step 179 of the flange 178. The cap 164 and plate 166 is each provided with annular oil seals 182 which surrounds the thrust sleeve 168.

The assembly 44 is mounted on the push rods 148 which extend through the plate 166 into sleeves 184 which are welded or otherwise secured to the plate 163 and plate 166, at the reduced ends of the assembly. A pin 186 passing through the sleeve 184 and push rod bar 148 secures the push yoke 44 to the rod 148 of each assembly 46.

The thrust sleeve 168 forward of the push yoke assembly 44 is provided with opposed cut-out portions or grooves 188, best seen in FIGURE 16. These cut-out portions extend through the sleeve and receive a horseshoe-shaped kelly bar lock member or keeper 190 which is slidably mounted within the cutout portions 188. The kelly bar, being generally square in cross sectional shape, as it passes through the square opening 189 in the sleeve 168 would not allow the legs 192 of the horseshoe-lock to fit properly within the cut-out portions. Thus two diametrically-opposed corners of the kelly bar 42 are notched as at 194. There are a plurality of these notches 194 along the length of the kelly bar so that it may be moved inwardly or outwardly from the collar 168 to the desired position and then locked to the sleeve 168 by positioning the horseshoe-shaped lock 190 in the grooves and slots, such as is illustrated in FIGURES 15 and 16. In order to retain the horseshoe-shaped lock or keeper 190 within the cut-out portions 188, a spring-actuated plunger means is provided which includes a plunger housing 196 mounted on sleeve 168, a plunger 198 slidably mounted within the housing and a spring 200 within the housing surrounding the plunger to urge the plunger toward the horseshoe lock 190. There is an opening 202 provided in the horseshoe lock to receive the plunger 198. Thus, when the lock is in position,

the hole 202 is aligned with the plunger and the plunger will be inserted within the hole to retain the lock in position. This horseshoe-shaped locking means has been found preferable over other forms of locking the kelly bar and push yoke assembly such as by pins and holes in the kelly, because the milled slots 194 in the corners of the kelly bar 42 will not weaken the kelly such as would happen if holes were drilled through the kelly.

The push yoke assembly 44 is further provided with 10 a pair of casing clamp and guide assemblies generally designated 204 each of which includes a track 206, best seen in FIGURE 13, which is secured to the front plate 163 by means of cap screws 208. Fitted within the track 206 is a clamp extension assembly including a 15 follower plate 210 slidably mounted within the track 206, and a pair of outwardly-extending arms 212, to which is secured a casing grip 214 having spaced-apart gripping fingers 216 and 218. The respective fingers 216 and 218 have arcuate opposing surfaces 220 and 222, and it will be noted that the arcuate surface 220 is struck on a smaller radius than the surface 222. The 20 reason for the difference in the arcuate surface sections is for the accommodation and gripping of various-sized casings or conduits. The gripping fingers 216 and 218 may be reversed in the track 206. As is illustrated in 25 FIGURE 20, the casing 64 has a relatively large diameter and thus engages the larger arcuate surface 222 of finger 216, whereas the illustration in FIGURE 12 shows the clamp extension 212 being reversed so that the 30 smaller arcuate finger 218 is positioned inside a casing 64" of relatively small diameter.

In order to secure the clamp extensions 212 to the casing 64, the respective extensions on either side of the push yoke 44 are moved back and forth, toward or away from each other within the track 206, and when the fingers 216 or 218 engage the casing 64, cap screws 224 extending through upper and lower flanges 226 of the track 206 will engage the follower plate 210 and hold the clamp extensions in a fixed position.

In order to join the auger flight 60 to the kelly bar 42 and lock the two together for joint rotation a key and keyway lock assembly 227 is provided. This assembly 227 includes a kelly bar adaptor 228, a pin 230 and a keyway configuration 244 on the end of the auger shaft 58, best seen in FIGURE 19. The adaptor 228 comprises a rectangular housing 232 having a square opening 234 into which the end of kelly bar 42 is inserted. Diametrically opposite holes 235 are provided in the housing 232 and a set pin 236 is inserted through one of the holes 235 through a corresponding opening 235a in the kelly bar 42 and into the opposite hole 235 of the housing (see FIGURE 17). In this manner, the adaptor is locked onto the kelly bar 42. The housing 232 is provided further with a tubular extension 238 having two opposite notched-out portions or keyways 240 and with opposed holes 242. The end 244 of the auger shaft 58 is notched at 246 complementary to notches or keyways 240 on the adaptor 228, and is provided with locking pin apertures 253. The pin 230 consists of a tubular shaft 248 having bores 250 and 250a extending therethrough, and centrally located between the respective ends of the pin 148 is an interrupted annular flange 252 forming segments or keys 252a. The axial length of the segments 252a is equal to the sum of the axial lengths of the notches 240 and 246. The pin 230 is inserted in the shaft 58 and tubular extension 238 so that the keys 252a will mate one half in each of the notches 246 and 240. In order to lock the assembly, pins 254 are inserted through the openings 242 and 250 in the pin and through openings 253 and 250a at the auger shaft end of the assembly. The circular auger shaft 58 and square kelly bar 42 will thus be joined and locked as an integral unit.

It should also be noted that each end of the auger shaft 58 is provided with keyways and locking pin aper-

tures so that one auger flight 56 may be secured to another auger flight as well as to the kelly bar 42.

Operation

After the pit 48 has been dug to the necessary depth to be drilled, adjacent the area 50, the horizontal boring machine 30 is placed in the pit 48 adjacent the back wall 49 of the pit and preferably in abutment thereto. The jacks 54 on the machine 30 are then positioned to engage the side walls of the pit and stabilize the machine and wedge it in position so that it cannot easily be shifted sideways or buckled. The pit 48 should be of sufficient length to accommodate the machine 30 plus an auger flight 56 and casing 64 with some room to spare for working in and around the machinery. An auger flight 56 encompassed by a conduit section 64 is then secured to the kelly bar 42 by means of the key and keyway assembly 227. With the auger shaft 58 and kelly bar 42 thus assembled, the casing clamp assemblies 204 mounted on the push yoke 44 are moved so that the gripping fingers 216 or 218 engage the inner surface of the end of the conduit 64. As previously mentioned, the arm extensions 214 are reversible so that the arcuate section of the fingers most nearly resembling a similar arcuate section of the casing may be used. FIGURE 20 illustrates the use of the larger arcuate finger for a relatively large diameter casing 64.

Once the casing is thus positioned in the casing grip, the motor 36 may be started and the transmission 40 engaged which will cause rotation of the rotary drive tube 92 and kelly bar 42 within the bearings 96, 98, and sleeve 168. This rotary motion to the kelly drive tube and kelly bar is accomplished through the transmission 40, upper sprocket gear 74 and reduction gearing heretofore described. Rotation of the kelly 42 imparts rotation to the auger 60 and drilling bit assembly 62 at the forward end of the auger. In the starting position the kelly 42 has been retracted rearwardly into the small bore 53. When it is desired to proceed with the drilling operation, and the auger is rotating, forward thrust of the auger 60 and casing 64 is accomplished through the pair of telescoping hydraulic rams 46 mounted in the base 32 and secured to the push yoke 44. The starting position for the ram assemblies requires that the hollow rod 132 and bar 148 be retracted within the base and pin 152 be inserted through the rod 132 and at the forward end of bar 148 to retain bar 148 within rod 132 for the first stroke of the ram assembly. Hydraulic fluid passes from the reservoir 260 through lines 262 and 158 into the cylinder 116, forcing the piston 130 forward, causing the hollow circular push rod 132 and push rod bar 148 to extend outward from the cylinder 116 forcing the push yoke and the casing forward. As the push rod 132 is forced forwardly, the kelly bar will also slide within the drive tube 92 from a position shown in FIGURE 1 to a position shown in FIGURE 3. It should be noted that the speed of the thrust of the hydraulic rams may be controlled in accordance with standard hydraulic practice dependent upon the soil condition encountered by the auger 60 as it penetrates the earth. Also it should be noted that the speed of rotation of the auger and kelly bar may be varied by control of the transmission dependent upon the conditions encountered during the drilling operation.

As the auger flight 60 penetrates the earth, dirt from the bore will be passed back into the pit 48 and any type of conventional conveyor may be employed to remove the dirt from the pit so as to keep the pit 48 relatively free of cuttings.

When the push rod 132 has reached its maximum stroke (best seen in FIGURE 3), the pin 152 is removed, and the push rod 132 is telescoped into the cylinder 116 to prepare for a second stroke to advance the auger and casing. When retracting the push rod 132 it is not necessary to lock the kelly bar 42 against slideable movement

due to the weight of the auger flight which will hold the kelly. After the push rod 132 has been retracted the pin 152 is inserted through the push rod 132 and hole 153 in push bar 148. As can be seen the push rod 132 is then in position for the second thrust which will advance the push bar 148, push yoke means 44, auger and casing.

When the push rod 132 has completed its second and final thrust relative to the auger flight 56 and casing 64 connected to the machine 30, a second auger flight 56' and casing 64' may be installed to lengthen the bore and casing.

To prepare for the new auger flight 58' the transmission 40 is disengaged so the kelly bar 42 will stop rotation and the coupling 227 is disconnected so that the kelly 42 will be free to slide rearwardly to a position as previously described and seen in FIGURE 1. The push rod 132 is retracted, moving the kelly bar and push yoke rearwardly toward the base 32 and the pin 152 is withdrawn. When the rod 132 is fully telescoped, the plunger lock assembly 106 is manipulated to engage the kelly bar 42 to prevent forward sliding movement of the kelly, push bar and push yoke while the push rod 132 is fully extended forward over the push bar 148 which remains stationary. When the push rod 132 is positioned coextensive with the bar, the pin 152 is inserted in openings 150 and the entire assembly is retracted to a position as illustrated in FIGURE 1.

Then the auger flight 58' and casing 64' may be positioned in the pit 48 so that the auger flight 58 and 58' may be connected by a coupling similar to coupling 227 and the casings 64 and 64' may be welded together as at 258. When the auger flight 58' and casing 64' are in position the boring and casing laying operation above described may be repeated.

Once the boring and casing laying have been completed the auger flights may be moved rearwardly in a manner previously described and removed a flight at a time for use again.

While the operation heretofore described related to simultaneously boring and laying a casing or conduit the machine 30 may also be utilized only in drilling or boring operation without the laying of casing. To accomplish this the casing 64 may be eliminated when the auger flight 58 is positioned in the pit 48 and the casing guides 206 on the push yoke assembly 44 may be removed.

While the invention is herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

Having described my invention, what I claim as new and desire to secure by Letters Patent is:

1. The combination of: a base platform, hydraulic telescoping ram means mounted on said base and extendable outward therefrom, a push yoke means mounted on said hydraulic ram means outwardly of said base, a kelly means slidably and rotatably mounted on said base platform and projecting from said base platform through said push yoke means and axially fixable therewith, said ram means, push yoke means and kelly means all having travel axes that lie in a common plane, coupling means on said kelly means adjacent said push yoke means, an auger flight including bit means operatively connected to said kelly means by said coupling means whereby rotation of said kelly means will rotate said auger flight, a hollow conduit encasing said auger flight and engageable by said push yoke means, said hydraulic ram means activatable to move said push yoke means, said kelly means, said auger flight and said conduit outward from said base platform whereby said auger flight will rotatably engage and bore the earth, and said push yoke

means will engage said conduit and slidably simultaneously urge said conduit into said bore, motor drive means on said base platform to drive said kelly means and means to activate said hydraulic ram means, and said push yoke means including adjustable, reversible conduit guide extensions which are each provided with a pair of spaced apart arcuate fingers struck on different radii, a selected one of said fingers being engageable with the interior surface of said conduit.

2. An earth boring and casing laying machine for use in a pit having a bottom, side walls and a first and second end wall adjacent the area to be bored and a relatively small bore in the earth extending parallel with said bottom and outward from the second end wall, said machine comprising a base platform mounted on said pit bottom, hydraulic ram means including a cylinder rigidly mounted on said base frame, a piston slidably positioned in said cylinder, a telescoping hollow ram push rod secured to said piston and extendable from said base platform forward toward said first end wall, a push yoke means mounted on said hydraulic ram means, a telescoping ram push bar slidably mounted in said ram push rod and having an end secured to said push yoke means, adjustable pin means to selectively fix the extent of telescoping of said ram push bar within said ram push rod, a kelly means slidably and rotatably mounted on said base platform extending through said push yoke means and axially fixable therewith, said kelly means slideable forward from said base platform toward said first end wall and rearward from said base platform through said second end wall into said relatively small bore, said ram means, push yoke means and kelly means all having travel axes that lie in a common plane, an auger flight including bit means projecting forward of said push yoke means, coupling means operatively connecting said auger flight and said kelly means whereby rotation of said kelly means will rotate said auger flight, a hollow conduit encasing said auger flight and engageable by said push yoke means, said hydraulic ram means activatable to urge said push yoke means, said kelly means, said auger flight and said conduit forward toward said first end wall whereby said auger flight will engage said first end wall and when rotating bore the earth, and said push yoke means will simultaneously slidably urge said conduit into said bore, and motor drive means on said base platform to drive said kelly means.

3. An earth boring and casing laying machine for use in a pit having a bottom, side walls and a first and second end wall adjacent the area to be bored and a relatively small bore in the earth extending parallel with said bottom and outward from the second end wall, said machine comprising a base platform mounted on said pit bottom, hydraulic ram means mounted on said base platform and extendable outward therefrom toward said first end wall, a push yoke means including a generally elongated housing mounted on said hydraulic ram means and including a front and back surface, a rotatable kelly receiving sleeve journaled in said housing, a kelly means slidably and rotatably mounted on said base platform extending through said kelly receiving sleeve, kelly keeper means on said sleeve to lock said kelly means and said sleeve together, said kelly means slideable forward from said base platform toward said first end wall and rearward from said base platform through said second end wall into said relatively small bore, said ram means, push yoke means and kelly means all having travel axes that lie in a common plane, an auger flight including bit means projecting forward of said push yoke means, coupling means operatively connecting said auger flight and said kelly means whereby rotation of said kelly means will rotate said auger flight, a hollow conduit encasing said auger flight and engageable by said push yoke means, said hydraulic ram means activatable to urge said push yoke means, said kelly means, said auger flight and said conduit forward toward said first end wall whereby said auger flight will

engage said first end wall and when rotating bore the earth, and said push yoke means will simultaneously slidably urge said conduit into said bore, and motor drive means on said base platform to drive said kelly means, 5 said kelly keeper means includes a pair of opposed grooves formed in said sleeve exteriorly of said housing and communicating with the interior of said sleeve, a generally U-shaped kelly keeper including generally parallel spaced apart legs, said legs each adapted to be fitted 10 within said grooves and engage said kelly whereby independent axial sliding movement of said kelly bar will be prevented.

4. An earth boring and casing laying machine for use in a pit having a bottom, side walls and a first and second end wall adjacent the area to be bored and a relatively small bore in the earth extending parallel with said bottom and outward from the second end wall, said machine comprising a base platform mounted on said pit bottom, hydraulic ram means mounted on said base platform and extendable outward therefrom toward said first end wall, a push yoke means mounted on said hydraulic ram means, a kelly means slidably and rotatably mounted on said base platform extending through said push yoke means and axially fixable therewith, said kelly means slideable forward from said base platform toward said first end wall and rearward from said base platform through said second end wall into said relatively small bore, said ram means, push yoke means and kelly means all having travel axes that lie in a common plane, an auger flight 20 including bit means projecting forward of said push yoke means, coupling means operatively connecting said auger flight and said kelly means whereby rotation of said kelly means will rotate said auger flight, a hollow conduit encasing said auger flight and engageable by said push yoke means, said hydraulic ram means activatable to urge said push yoke means, said kelly means, said auger flight and said conduit forward toward said first end wall whereby said auger flight will engage said first end wall and when rotating bore the earth, and said push yoke 30 means will simultaneously slidably urge said first conduit into said bore, and motor drive means on said base platform to drive said kelly means, said coupling means includes a hollow ended portion mounted on said kelly means, a second hollow ended portion on said auger flight, each hollow ended portion being provided with a 40 pair of generally diametrically opposed keyways, a key pin provided with a pair of flange keys intermediate the ends thereof and adapted to be inserted into both hollow ended portions whereby said hollow ended portions may be drawn into abutting relation and said keys each inter-fitted generally equally within respective complementary keyways of each hollow ended portion, and pins insertable through said hollow ended portions and said key pin to lock said kelly means and said auger flight together.

5. The combination of: a platform, a pair of spaced apart hydraulic telescoping push rams mounted on said platform, a push yoke means carried by said hydraulic telescoping push rams and extending therebetween, a kelly bar slidably and rotatably mounted on said platform and projecting through said push yoke means, said hydraulic telescoping push rams, push yoke means and said kelly bar all having travel axes that lie in a common plane, releasable kelly keeper means to lock said push yoke means and said kelly bar for simultaneous axial movement, coupling means on said kelly bar forward of said push yoke means, an auger flight including bit means operatively connected to said kelly bar by said coupling means whereby rotation of said kelly bar will rotate said auger flight, a hollow conduit encasing said auger flight, said push yoke means including conduit guide means for releasably non-fixedly receiving said conduit, a motor drive means on said platform to rotate said kelly bar, a hydraulic fluid system to activate said hydraulic telescoping push rams along said travel axes whereby said 50 push yoke means, said kelly bar, said auger flight and said

11

conduit may all be simultaneously moved on an outward stroke from said platform to bore the earth and simultaneously position said conduit in said bore, and said push yoke means and said kelly bar being retractable on an inward stroke toward said platform by said hydraulic push rams and said conduit guide means being freely disengaged from said conduit so that said conduit will remain in the position assumed on said outward stroke.
